CLAIM

The ornamental design for a slide phone, as shown and described.

DESCRIPTION

FIG. 1 is a front view of a slide phone of our new design; FIG. 2 illustrates a top view thereof;

FIG. 3 illustrates a left side view thereof;

FIG. 4 illustrates a right side view thereof;

FIG. 5 illustrates a bottom view thereof;

FIG. 6 illustrates a back view thereof;

FIG. 7 illustrates a back view with the slide phone in an open position;

FIG. 8 illustrates a left side view with the slide phone in an open position; and,

FIG. 9 illustrates a front view with the slide phone in an open position.

The outer periphery of the keypad portion of FIG. 10 shown in broken lines represents the bounds of the claimed design while the numerals and the grid defining the individual keys in broken lines are directed to environment and are for illustrative purposes only; the broken lines form no part of the claimed design.
